SASH MOUNTING FOR REVERSIBLE WINDOWS

Original Filed Feb. 19, 1925

Patented Mar. 19, 1929.

1,705,830

UNITED STATES PATENT OFFICE.

JAMES ADAMS STEWART, OF OAKLAND, CALIFORNIA.

SASH MOUNTING FOR REVERSIBLE WINDOWS.

Original application filed February 19, 1925, Serial No. 10,221. Divided and this application filed January 16, 1926. Serial No. 81,634.

My invention relates to swinging-sash mountings of the type which permit the full or the limited reversal of the sashes. This application has been divided from my original application Serial No. 10,221, filed in the Patent Office February 19, 1925, and which relates more particularly to the combination of a swinging and sliding sash mounted in a frame by means of a track secured to the frame, and a shoe slidably engaging the track and secured to the sash. The present application on the other hand relates to the support or fixture per se which is adapted to the use of mounting windows of the swinging and slideable type.

In the use of mountings of the character described, the sash is usually pivotally connected to shoes which engage in tracks positioned at opposite sides of the window frame opening, and in order that the sash will be firmly held in its different positions suitable means are provided for retarding the movement of the shoes relative to the tracks. Such means have usually comprised a resilient member cooperating with the shoe and track to frictionally clamp them together, the degree of resistance to the movement of the shoe depending on the clamping pressure. When the sash is in an open position, a portion thereof usually extends outwardly from the window frame, and as may be readily understood considerable pressure is thus necessary to frictionally hold the sash against movement, particularly when a wind of appreciable strength is blowing. It will be obvious, however, that a clamping pressure sufficient to frictionally hold the sash firm under ordinary conditions usually entails such resistance to the movement of the sash that opening or closing of the window may be effected only with difficulty. In accordance with the foregoing, it is an object of my invention to provide a swinging mounting for the sash which will cause the sash to be held in its different open positions, without requiring the use of manually operated fastening means, or entailing, as above mentioned, the employment of a clamping pressure such as will interfere with the desired

smoothness and ease of operation of the sash. 50
Another object of the invention is to provide a device of the character described in which the resilient member is of such form and so arranged that a relatively minimum deformation thereof will be required. 55

A further object is to provide a device of the character described which makes for simplicity, compactness, and low cost of manufacture.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims. 60 65 70

Referring to said drawings:

Figure 1 is a sectional plan view of a portion of a window equipped with the mounting of my invention, the sash being indicated in dotted lines and shown in an open position. 75

Figure 2 is a vertical sectional view of the window showing the sash in closed position, a large portion of sash being removed in order to reduce the size of the figure. 80

Figure 3 is a perspective view of a portion of the mounting of my invention.

Figure 4 is a fragmentary sectional detail of a modified form of the pressure element.

The mounting of my invention in its present form is designed to provide semi-reversibility of the sash and is illustrated in connection with a window 4 of the casement type. Each sash is arranged to be provided with two mountings, one at the top and the other 90 at the bottom thereof. As here shown, each mounting comprises a track 6 which is arranged to be positioned at each of the opposite sides of the frame opening 7. The track is formed with a base plate 8 which is arranged to sit in and against the head or the sill of the window frames, as the case might be. Attachment of the track to the 95

frame is preferably effected by means of screws 9 which extend through openings 12 formed in the base plate.

Angularly disposed with respect to the plate is the guide proper, denoted in general by the numeral 13, and which, as here shown, comprises a series of longitudinally aligned guide portions 14 formed by tongues punched in and offset from the plate. Each track has 10 associated therewith a shoe 16 which is arranged to be moved relative thereto and to be guided in such movement by the guide 13.

Pivoted to each shoe, such as by means of pivot bolts 17, is a plate 18. The plates are 15 arranged to extend along opposite stiles 19 of the sash 21 and adapted to be rigidly secured to the sash. The latter in addition to being pivoted to the shoes, is connected to the frame by links 22 in such manner that recip- 20 rocation of the shoes will cause oscillation of the sash, the extent of such movement being here designed to allow the sash to be moved from a fully closed position to one of semi-reversal of vice versa.

25 The shoe 16 comprises a body 27 and angularly disposed bearing members 28 and 29 which are arranged to slide upon the plate at opposite sides of the guide member 13, the body portion 27 being arranged to lie spaced 30 from the plate and disposed across the free edge of the guide 13. Engagement of the shoe with the guide 13 is preferably effected by causing the bearing 28 to engage therewith, such engagement being maintained by 35 means of a spring 31 which is fixed to the shoe and is arranged to bear against the guide. The spring is positioned to lie between the body member 27 and the base 8, and preferably abuts against the bearing 40 member 29. Tongues 32 assist in holding the spring against the member 29, and co-operation of such tongues with an offset 33 of the spring prevents lateral displacement of the spring with respect to the shoe.

45 Transverse disengagement of the shoe from the track is prevented by a flange 34 formed at an edge of the track. It will be noted by reference to Figure 1, that a comparatively large space is provided between guide 13 50 and the bearing member 29, and that a spring of relatively large size may thus be interposed between such members. In this manner the deformation of the spring as a whole may be considerable without imposing ap- 55 preciable strain thereon. It will also be noted that positioning of the spring in the manner described, permits of the shoe being both guided by and kept in resilient engage- 60 ment with the track by the use of but the single guide member 13.

It will be clear that owing to the spring pressure holding the guide 13 and bearing 28 in frictional engagement, the movement of the shoe relative to the track will be to a

certain extent retarded. However, such 65 pressure is of an amount calculated to merely hold the sash steady against forces of relatively weak magnitude, and for this reason the resistance to the movement of the sash thus produced will not appreciably impair 70 the smooth and easy operation of the sash. Since the aforementioned means are thus inadequate to enable the sash to resist unintended displacement when in an open position and subjected to strong forces, means 75 are provided for enabling the sash to resist such displacement and which at the same time do not appreciably effect the ease of operation of the sash. In the present embodiment of the invention such last means is incorporated with the preceding described 80 means and requires practically no additional parts. As clearly shown in Figure 3 the series of portions 14 comprising the guide member 13 are separated from each other 85 by spaces 36, and suitable means are provided on the shoe to automatically engage in or disengage from such spaces upon movement of the sash, whereby the movement of the sash upon such engagement, will be resisted 90 to a greater degree than that with which its movement is resisted, by reason of engagement of the spring directly against the face of the guide portions 14. In the preferred embodiment of the invention said space-engaging-means on the shoe is provided by direct use of the spring 31. As shown in Figures 1 and 2, the portion of the spring arranged to engage the guide portions 14 is 95 bent to provide an outward transverse offset 100 37 which will readily enter the spaces 36 when moved opposite same. With the offset thus disposed in one of such spaces and forcibly held against the adjacent ends of adjoining portions 14, considerable resistance will be 105 provided against displacement of the sash. Release of the spring from engagement in a space may be effected by impressing a sudden but vigorous force against one of the side stiles 39 of the sash. After the sash has been 110 moved sufficiently to cause at least partial disengagement of the spring with the space, continued movement thereof will be comparatively free and easy. It will be readily understood that by accelerating the movement 115 of the sash, the spring will not have opportunity to adequately engage in the spaces and no appreciable resistance to the movement of the sash will be caused.

In Figure 4, I have shown a slightly modified form of the space-engaging means. As here shown a roller 41 is carried by the spring and is arranged to bear against the guide portions as well as to engage the spaces.

It will now be clear that the device of my invention is of extremely simple construction and enables the sash to be positively held in open as well as closed positions, without un-

due stiffness in the operation of the sash, and without the use of manually operable fastening means.

I claim:

5. 1. In a window fixture of the character described; a guide plate arranged to be positioned at a side of the window frame opening and comprising a base by which the plate may be attached to the frame, and longitudinally spaced guide portions extending angularly from the base; a shoe having a body portion overlying said guide portions, and bearing portions arranged to ride over said base and positioned to lie at opposite sides of said angular guide portions, and a spring 70 detent carried by said shoe and arranged to successively engage said guide portions and the spaces therebetween when the shoe is moved along the plate.
10. 2. In a window fixture of the character described; a guide arranged to be positioned at and fixed to a side of the window frame opening and comprising a plate member providing a base portion and having longitudinally aligned and spaced guide portions extending therefrom, a shoe having portions thereof engageable with said base at each of the opposite sides of said guide portions, a spring carried by said shoe and lying at one of said 15 sides of the guide portions and, means on the spring arranged to bear against said last mentioned side of the guide portions or in the spaces therebetween whereby the portion of the shoe at the other side of said guide portions may be frictionally held against the 20 guide portions.
25. 3. In a window fixture of the character described, a guide member arranged to be positioned at a side of the window frame opening and having associated therewith aligned spaced portions extending longitudinally along said side, a sash supporting shoe mounted to overlie said portions and arranged for 30 slidably engagement with said guide member, and means carried by the shoe arranged to resiliently engage said guide member portions and seat in the spaces therebetween.
35. 4. In a fixture for windows of the character described, a guide member arranged to be positioned at a side of the window frame opening and comprising a base having an angular disposed flange at one edge thereof, spaced flange portions struck up from said base and extending parallel to the first flange whereby a channel will be defined therebetween, a shoe arranged to move upon said member and having parallel bearing faces, one of which is arranged to engage in said channel, a spring pressed member fixed to 40 said shoe and arranged to successively press against said second flanges and seat in the spaces therebetween as the shoe is moved along the guide, and a sash plate pivoted to said shoe.
45. 5. In a fixture for reversible windows of the character described, a frame provided with an opening, a track interrupted at intervals by spaces and arranged to be positioned adjacent said opening, a shoe movable along said track, arranged to be pivoted to a sash 70 and a spring pressed detent carried by said shoe and disposed to resiliently engage the track and to enter said spaces to retard the movement of said shoe on said track to a greater degree at said spaces than at the portions of the track between said spaces.
50. 6. In a window fixture of the character described; a guide plate arranged to be positioned at a side of the window frame opening and comprising a base by which the plate may be secured to the frame, and a longitudinally extending guide portion angularly disposed to said base; a shoe comprising a body portion overlying said guide portion, and bearing portion extending angularly from said body positioned at opposite sides of said guide and arranged to engage said base, and a spring lying between said base and overlying body portions operatively interposed between said guide portion and one of said bearing 85 portions whereby the other bearing portion will be maintained in resilient engagement with said guide portion.
55. 7. In a fixture of the class described, a guide member arranged to be positioned at a side of the window frame opening and comprising a base portion having spaced flange portions struck up angularly therefrom and disposed in mutually coplanar relation, a sash supporting shoe arranged to move along said 90 member and having a bearing face arranged to engage along corresponding sides of said flange portions and a spring pressed member fixed to said shoe and arranged to successively press against said flange portions at opposite 95 sides thereof from the engagement of said bearing face therewith and seat in the spaces therebetween as the shoe is moved along the guide.
60. 8. A window support including a track having a base having one side thereof disposed at an angle and having the free edge of said side extended inwardly and lying parallel to the base, a shoe having a flange on one side thereof engaging the base between the sides of the latter and having a flange on its opposite side engaged over said angular side of the base and the inwardly extended free edge thereof, latch members carried by the shoe, keeper means on said inwardly free edge of said side of the base, a substantially L-shaped plate formed to be secured to a window sash and having one side pivoted to the top of the shoe and having its opposite side extending over said flange of the shoe and engageable with the base of the track, and an arm pivoted to the plate and to the track.
65. 9. A window support including a track having a base and an angular side, an angular 100
70. 10. A window support including a track having a base and an angular side, an angular 105
75. 11. A window support including a track having a base and an angular side, an angular 110
80. 12. A window support including a track having a base and an angular side, an angular 115
85. 13. A window support including a track having a base and an angular side, an angular 120
90. 14. A window support including a track having a base and an angular side, an angular 125
95. 15. A window support including a track having a base and an angular side, an angular 130

shoe having a top side engaging the angular side of the track and having its other side engaged with the base of the track, a plate formed for securedment to a window sash and 5 being pivoted to the shoe and having an angular part extending over the said other side of the shoe, an arm pivoted to the plate and to the track, said angular side of the base of the track being formed with an inwardly extend-

ing part which overlies the base and which 10 is formed with spaced depressed parts, and a tongue struck outwardly from the top side of the shoe and engageable with the depressed parts.

In testimony whereof, I have hereunto set 15 my hand at Oakland, California, this 6th day of January, 1926.

JAMES ADAMS STEWART.
